(57) CLAIM

The ornamental design for a play tent, as shown and described.

DESCRIPTION

FIG. 1 is a perspective view of the present invention.

FIG. 2 is a side view thereof;

FIG. 3 is the opposite side view and mirror image of FIG. 2; FIG. 4 is a front view thereof;

FIG. 5 is a rear view thereof;

FIG. 6 is a top view thereof; and,

FIG. 7 is a bottom view thereof.

The broken lines in FIG. 1 are for showing the environment in which the article resides and form no part of the claimed design.
